UNITED STATES PATENT OFFICE.

HARRY J. FLOOD, OF CHICAGO, ILLINOIS.

MACHINE FOR COMPRESSING MATERIAL INTO FORM.

SPECIFICATION forming part of Letters Patent No. 734,531, dated July 28, 1903.

Application filed August 9, 1901. Serial No. 71,434. (No model.)

To all whom it may concern:

Be it known that I, HARRY J. FLOOD, a citizen of the United States, residing in the city of Chicago, county of Cook, and State of Illinois, have invented a new and useful Improvement in Machines for Compressing Material into Form, of which the following is a specification.

My invention relates to machines for compressing material into form, and is especially applicable to brick-machines of the type well-known as "toggle-machines."

Attention is hereby directed to a separate application for patent on the type of mold herein shown, said application having been filed on the 28th day of August, 1902, Serial No. 121,269.

The objects of my invention are, first, to provide means for facilitating the positioning of the lower plungers upon the lower cross-head; second, to avoid the danger of the clay or other material gaining access to that portion of the surface of the lower cross-head which forms a seat for the lower plungers and supports thereof, and, third, to provide the other details hereinafter set forth. I attain these objects by the mechanism illustrated in the accompanying drawings, in which—

Figure 1 is a plan view of the mold-table. Fig. 2 is a vertical sectional view taken on the line 2 2, Fig. 1, showing the mold-table, lower portions of the machine-frame, the lower cross-head, and connected parts. The lower plungers and supporting top plate are shown seated upon the lower cross-head. Fig. 3 is a sectional view of the parts illustrated in Fig. 2, the lower plungers and top plate being shown in a raised position above the lower cross-head. Fig. 4 is a sectional view of the mold-table in a vertical direction on the line 4 4, Fig. 1, and showing the position of the partition-plates. Fig. 5 is a vertical sectional view of the mold-table, taken on the line 5 5, Fig. 1. Fig. 6 is a vertical sectional view of the mold-table, taken on the line 6 6, Fig. 1, and indicating also the arrangement of the lower plungers and cross-head. Fig. 7 is a sectional view of the mold-table, taken on the line 7 7, Fig. 1. Fig. 8 is a detail view of lower cross-head and connected parts. Figs. 9 and 10 are top and transverse vertical sec-

tional views, respectively, of the parts shown in Fig. 8. Fig. 11 is a top view in detail of the spring-washer employed in connection with the plunger-stems. Fig. 12 is an enlarged side view of a spring-washer. Fig. 13 is a transverse vertical sectional view of the machine, taken through the molds. Fig. 14 is a detail sectional view showing the devices for adjusting the depth of mold.

Similar characters refer to similar parts throughout the several views.

The parts *a a* represent the lower portion of the main framework of the machine, whereon the mold-table is supported. Said mold-table comprises the front piece or cross-block *b* and back piece or cross-block *c*, which are substantially symmetrical in form and are provided with the recesses *b' b'* and *c' c'*, respectively, for receiving the extremities of the end blocks *d d*. Said front and back pieces *b* and *c* of the mold-table, which are of massive construction to afford great rigidity and strength, extend across the machine and are bolted to the side frames *a a* by means of the cap-screws *a' a'*. The side frames *a* are apertured to loosely receive said cap-screws to permit adjustment of the parts of the mold-table. The front apron *e* and back apron *f* are bolted to the front and back parts, respectively, of the mold-table. The front and back pieces of the mold-table are drawn firmly to a bearing upon the said end blocks in a direction from front to rear of the machine by means of heavy bolts *g g*, which fit loosely in said front and back pieces and also by preference pass through said end blocks, which latter are suitably recessed to receive said bolts. In the transverse direction said end blocks are forced inwardly toward the center of the machine by means of the set-screws *h h*. Said front and back pieces or cross-blocks *b* and *c* of the mold-table are suitably drilled and tapped at the recesses *b'* and *c'* for receiving said set-screws, while the side frames are apertured in such a manner as to receive said set-screws loosely. The tightening of said set-screws forces said end blocks firmly onto the mold-lining plates, as will hereinafter appear.

The molds *i* are formed by the end liners *j* and side liners *k*, which consist, preferably,

- of steel plates having polished inner faces, said plates extending from front to rear between the parts *b* and *c* of the mold-table. The extremities of the partition-plates *m* and 5 side liners *k* and also the back or rear sides of the end liners *j* are mortised to fit into the correspondingly-chambered front and back parts *b* and *c* of the mold-table. It is evident that when the bolts *g* are screwed 10 tight the side liners and partition-plates are prevented from moving in the direction from front to rear. The motion of the side liners and partition-plates in a transverse direction is prevented by the end blocks *d*, held by the 15 set-screws *h*, the end liners *j* serving as distance-pieces to spread said side liners and preserve the proper width of mold. The pressure of the side liners *k* against the end liners *j* holds the latter firmly in position. 20 It follows, therefore, that the strain upon the mold-plates due to the tendency of the clay or other material to expand laterally under compression is taken up in a transverse direction by the parts *b* and *c* of the 25 mold-table, which are of ample proportions and at the same time simple in construction. Moreover, the pressure upon the ends of the molds is also taken up by said parts *b* and *c*, which being drawn together by the bolts *g* 30 are subjected to a transverse or breaking strain. Consequently the mold-table is not only self-contained, but consists of but four principal pieces—to wit, the end blocks *d* and parts *b* and *c*.
- 35 In operation when it is desired to alter the size of the mold or renew worn parts the screws *h* and bolts *g* are loosened sufficiently to permit the end blocks and parts *b* and *c* of the mold-table to be backed off, so that the 40 mortised end and side liners may be removed. The size of the molds will be determined by the thickness of said lining-plates.
- The lower plungers *n*, which are designed to reciprocate vertically in the molds *i*, consist of castings provided upon their top surfaces with the face-plates *o*. Said plungers are secured by means of tap-bolts to the top plate *p*, which extends across the machine beneath the molds *i*. During compression said 45 top plate *p* seats upon the lower cross-head, which is a built-up member composed of the side plates *q*, secured, preferably, by riveting to the end blocks *r*. The cross-head is bolted to the side bars *s*, which are moved 50 vertically by any suitable mechanism. After a brick has been formed in the mold it is delivered onto the front apron in the manner well understood in the art, and it is desirable that the lower plungers shall remain flush with 55 the top of the mold during such delivery and subsequently drop quickly to afford the requisite depth of mold. On account of the difficulty of imparting the proper motion to the lower cross-head itself the lower plungers are 60 not attached directly thereto, but are so contrived as to rise therefrom and be temporarily sustained at the top of the mold by 65 springs in the manner now to be described. The plunger-stems *t* are attached to the top plate *p* by means of the bolts *u* and to the cross-bar *v* by means of the bolts *w*.
- In order to afford an even upper surface to the top plate *p*, said plate is recessed to receive the heads of said bolts *u*. The cross-bar *v* is adapted to slide vertically in the 70 ways *x*, provided in the auxiliary frame *y* beneath the main framework of the machine. The upward travel of said bar is limited by the contact of the bolts *l*, mounted in said bar, with the stops *2*, formed in said frame *y*, and the parts are so proportioned that said bolts will engage said stops when the lower plunger face-plates are flush with the top of the molds. The lever *3* has a bearing upon said bar *v* and is pivotally connected at its 75 forward extremity to the lower extremity of the vertical adjusting-rod *4*. As best illustrated in Fig. 14, the vertical adjustment of said rod *4* is determined by means of the sleeve *5*, which is threaded to engage said rod *4* and has a bearing in the gear-casing *6*. Said casing is supported from the part *b* of the mold-table. The sleeve *5* has formed at its 80 upper portion the bevel gear-wheel *7*, which meshes with the bevel gear-wheel *8*, mounted upon the horizontal shaft *9*. Said shaft, which has a bearing in the bracket *b*, pivotally supports said gear-casing and is rotated by means of the hand-wheel *10*, and the arrangement is such that the rotation of said shaft results 85 in the vertical movement of said rod *4*, and consequently determines the position of the forward extremity of the lever *3*.
- In this construction the top plate *p*, stems *t*, and lower plungers *n* are independent of 90 the lower cross-head and are raised therefrom by the springs *11*, which in the present construction encircle said stems *t* and act against the washers *12* beneath the said top plate *p*. The lower extremities of said springs seat 95 upon the spring-washers *13*. Said washers *13* are removably mounted in the lower cross-head by means of the pins *14*, the shanks whereof are inserted in apertures *15* in the side plates *q* in such a manner that the heads 100 *16* of said bolts project inwardly and fit into the sockets *17* in said washers. This open construction of the lower cross-head prevents accumulation of dust, which may accidentally get beneath the top plate *p*, for the reason that any dust so entering would drop 105 downward through said cross-head and would not be retained thereby. The springs impart a tendency for the top plate *p* to rise from the cross-head; but it is necessary that the 110 lower plungers shall move downward at the proper time to afford sufficient depth of mold. This lowering of the lower plungers consequent upon the downward movement of the 115 lower cross-head *q* is accomplished by means 120 of the forked rod *18*, which is pivotally attached to said lower cross-head and engages the pin *19*, mounted upon the lever *3*. Said rod and pin virtually form a movable pivot 125 130

or bearing for said lever 3, and it is evident that in operation when said pin and forked rod are in engagement a raising or lowering of the adjusting-rod 4 will have a reverse effect upon the top plate and lower plungers relatively to the lower cross-head.

- In order to prevent the access of clay or other material to the contact-surfaces between the top plate *p* and side plates *q*, guards 20, 10 consisting, preferably, of sheet metal, are attached to said top plate, as shown in Figs. 2 and 3. This considerably simplifies and improves upon the constructions heretofore employed, for when the lower plungers are permitted to rise individually from the cross-head it is difficult to protect the seating-surfaces from dust, and an accumulation of dust will create a tendency to wrest the plungers from the plunger-stems.
- 20 One of the important features of the present invention lies in the mounting of the lower plungers upon a common top plate, since by this means the plungers may be mounted without the necessity of considering 25 the plunger-stems—that is to say, the plungers may be shifted upon the top plate regardless of the positions of the stems. By employing this construction in connection with the mold-table above described it is possible to alter the number of molds in a machine and still maintain symmetrical disposition and spacing of the molds.

By substituting plungers of the required size and correspondingly altering the molds 35 brick of any desired dimensions may be made.

It is obvious that as the top plate *p* is secured to each one of the plunger-stems one or two of the bolts *u* may become loosened without permitting the springs 11 to throw the 40 lower plungers *n* above the top of the mold, to thereby interfere with other parts of the machine. In the construction heretofore employed, in which each plunger is individually secured to its plunger-stem, the loosening of 45 any one plunger from its stem would permit such plunger to rise too far, with the danger of wrecking the machine. By the new construction therefor the danger of the lower plungers accidentally rising by accident too 50 far is materially lessened.

Although the part *p* in this present machine is shown to be substantially a parallelepiped and is herein referred to as a "plate," I do not desire to limit myself to this particular 55 form. The part *p*, although directly attached to the lower plungers, is movable relatively to the lower cross-head and is partially independent thereof. Said part *p* may therefore be appropriately considered as being a secondary cross-head.

What I claim as new, and desire to secure by Letters Patent, is—

1. In a machine for compressing material into form, the combination of molds; upper 60 and lower plungers; a top plate carrying said lower plungers; springs supporting said top plate; and a lower cross-head forming a seat

for said top plate, said cross-head having a chamber therein open top and bottom where- 70 in said springs are mounted, said springs being thereby accessible from the bottom of the cross-head.

2. In a machine for compressing material into form, the combination with the molds and upper and lower plungers sliding there- 75 in, of a lower cross-head open top and bottom; a top plate seating thereon; means for raising said top plate independently of said cross-head; and means extending upward through said cross-head from a point beneath 80 the same for limiting the rise of said top plate from said cross-head.

3. In a machine for compressing material into form, the combination with the molds and upper plungers of a lower cross-head, a 85 top plate seating thereon, lower plungers mounted upon said top plate, plunger-stems secured to said top plate, springs supported at one extremity from said cross-head and at the other extremity acting upon said top plate 90 to raise the same from its seat; and means for limiting the rise of said top plate from said cross-head.

4. In a machine for compressing material into form, the combination with the molds, 95 and upper and lower plungers sliding therein; of a top plate carrying said lower plungers, a lower cross-head consisting of parallel plates secured to end blocks, springs between said parallel plates acting upon said top plate to 100 yieldingly support the same on said cross-head, washers for supporting said springs, and pins removably mounted in said parallel plates of the cross-head for supporting said washers.

5. In a machine for compressing material into form, the combination with the molds, upper and lower plungers sliding therein, a cross-head and a top plate for supporting the lower plungers, of springs sustaining the top 110 plate yieldingly on the cross-head; a cross-bar sliding in vertical guideways below said cross-head; and stems connecting said top plate with the said cross-bar.

6. The combination with a mold, of upper 115 and lower plungers sliding therein, a top plate for carrying the lower plungers, a cross-head for supporting said top plate, springs sustain- 120 ing the lower plunger yieldingly on the cross-head, a cross-bar sliding in vertical guide- 125 ways below the said cross-head, stems connect- ing the said top plate with the said cross-bar, and a lever pivotally connected with said cross-bar and engaged with a fulcrum upon the machine-frame, said lever being adapted for contact with a part of or upon the lower cross-head which limits the upward move- 130 ment of the top plate and lower plungers.

7. The combination with a mold, of upper 130 and lower plungers sliding therein, a top plate carrying the lower plungers, a cross-head for supporting the top plate, a spring or its equivalent sustaining the top plate yieldingly on the lower cross-head, a lever connect-

ed with the top plate and having a fulcrum upon the machine-frame, a rod connected to the lower cross-head and forked or slotted at its lower end, and a pin secured in said lever 5 and adapted to engage the forked or slotted end of said guide-rod to limit the upward movement of the top plate and lower plungers at the time of filling the mold.

8. The combination with a mold, of upper 10 and lower plungers sliding therein, a plate whereon the lower plungers are mounted, a cross-head for supporting said plate, springs sustaining said plate yieldingly on the lower cross-head, a cross-bar located below the lower 15 plungers and having sliding connection with the machine-frame, stems passing through the lower cross-head and connecting the said plate with the said cross-bar, a lever fulcrumed upon the machine-frame and pivotally connected with the said cross-bar, and a stop on the lower cross-head adapted for contact with the said lever to limit the upward movement of the said plate under the action of said springs.

25 9. The combination with a mold, of upper and lower plungers sliding therein, a cross-head, a continuous plate whereon said lower plungers are mounted, springs sustaining said plate yieldingly on the lower cross-head, a 30 lever connected with the said plate, a vertically-movable threaded adjusting-rod, a pivot connecting said rod with said lever, a revolving sleeve threaded to engage said rod, a frame affording bearings for said sleeve and 35 mounted upon pivotal supports or trunnions to afford freedom of lateral movement in the lower end of said adjusting-rod, substantially as described.

10. In a machine for compressing material 40 into form; molds; upper and lower plungers sliding therein; and a lower cross-head comprising plates secured together at a slight distance apart; in combination with a top plate seating upon said parallel plates and 45 supporting said lower plungers; and means extending between said parallel plates for yieldingly supporting said top plate and tending to raise the same from said parallel plates.

11. In a machine for compressing material 50 into form, the combination of molds, upper and lower plungers sliding therein, a top plate carrying said lower plungers; springs supporting said top plate; and a built-up lower cross-head forming a seat for said top plate, 55 said cross-head comprising parallel plates secured together a sufficient distance apart to receive said springs between them, whereby access may be had to said springs from beneath the cross-head.

60 12. In a machine for compressing material into form, the combination with the molds, upper and lower plungers sliding therein and a lower cross-head, of a top plate for sup-

porting said lower plungers; means for sustaining said top plate yieldingly on the cross-head and tending to raise said top plate therefrom; and means adjustable at a point outside of said cross-head for controlling the height to which the top plate may rise from said cross-head.

70 13. In a machine for compressing material into form, the combination with the molds, upper and lower plungers sliding therein and a lower cross-head, of a top plate for supporting said plungers; means for sustaining said top plate yieldingly on the cross-head and tending to raise said top plate therefrom and means adjustable at a stationary point for controlling the height to which the top plate may rise from said cross-head.

75 14. In a machine for compressing material into form, the combination of molds; upper and lower plungers sliding therein; a lower cross-head comprising parallel plates secured together at their ends and having a space between them; a top plate seating upon said parallel plates and carrying the lower plungers; and said top plate covering the space between said parallel plates to thereby prevent the access of clay or other foreign matter to the parts beneath; and means for yieldingly supporting said top plate, said supporting means extending between said parallel plates and tending to raise said top plate therefrom.

80 15. In a machine for compressing material into form, the combination of molds; upper and lower plungers sliding therein; a lower cross-head open top and bottom; a top plate seating upon said parallel plates and carrying the lower plungers; stems secured to said top plate for limiting the rise thereof, said stems extending downward through and beneath said cross-head; and springs for yieldingly supporting said top plate and tending 85 to raise the same from said parallel plates.

16. In a machine for compressing material into form, the combination of molds; upper and lower plungers sliding therein; a lower cross-head comprising parallel plates secured 90 together at their ends and having a space between them; a top plate seating upon said parallel plates and carrying the lower plungers; stems secured to said top plate for limiting the rise thereof, said stems extending 95 downward through said cross-heads; springs for yieldingly supporting said top plate and tending to raise the same from said parallel plates, and means connected to said stems below said cross-head for adjusting the height 100 to which said top plate may rise from said cross-head.

HARRY J. FLOOD.
